UNITED STATES PATENT OFFICE.

OLIVER S. JENNINGS, OF WILKINSBURG, PENNSYLVANIA, ASSIGNOR TO WESTINGHOUSE ELECTRIC AND MANUFACTURING COMPANY, A CORPORATION OF PENNSYLVANIA.

REVOLVING FAN.

1,270,832.

Specification of Letters Patent.

Patented July 2, 1918.

Application filed January 6, 1915. Serial No. 791.

To all whom it may concern:

Be it known that I, OLIVER S. JENNINGS, a citizen of the United States, and a resident of Wilkinsburg, in the county of Allegheny and State of Pennsylvania, have invented a new and useful Improvement in Revolving Fans, of which the following is a specification.

My invention relates to revolving fans, 10 and it has special reference to gyratory electric fans that are adapted to turn on an axis of rotation while simultaneously and automatically turning around an external axis of revolution.

One object of my invention is to provide a 15 gyratory fan of simple, compact and durable construction which shall be provided with positively actuated mechanical means for effecting the rotation of the fan support 20 by power derived from the rotating shaft that carries the fan blades.

Another object of my invention is to provide a fan of the above-indicated character 25 which may be readily adjusted to deliver air either horizontally or at various angles of inclination without disengaging the gearing which causes the revolution of the fan structure.

In the accompanying drawings, Figure 1 30 is a side view, partially in elevation and partially in section, showing a revolving fan constructed in accordance with my invention and provided with two sets of rotating fan blades. Fig. 2 is a plan view, partially 35 in section, showing the driving belt mechanism and the mechanism for varying the inclination of the fan motors, and Fig. 3 is a sectional view taken substantially along the line III—III of Fig. 1.

The structure shown in the drawing 40 comprises two fan motors 1 and 2 pivotally supported at 3 and 4 upon opposite sides of a bracket 5 that is rotatably suspended from a hanger rod 6. To the screw-threaded 45 lower end of the hanger 6 is attached a casting 7 provided, at its lower end, with a pulley groove 8 and also provided with inwardly extending arms 9 that support an internally screw-threaded member 10 which 50 is engaged by the screw-threaded upper end of a vertical rod 11. The lower end of the rod 11 is also screw-threaded and engages threads in a bottom casting 12, the exterior contour of which is substantially spherical. 55 The outside of the bracket 5 is also spheri-

cally curved to correspond to the bottom casting 12, and a hood 13 is disposed above the bracket 5 and rests upon a shoulder 14 formed in the casting 7. The members 5, 12 and 13 together compose a generally 60 spherical structure. The bracket 5 is provided with an upwardly extending sleeve 15 that surrounds the rod 11, and ball bearings 16 are disposed in a suitable ball race between the sleeve 15 and the rod 11. 65

As the fan motors 1 and 2 may be of any 70 desired type, the details of their structure will not be described. Secured to the rear end-bell of each of the fan motors is a gear box 17, and the gear box 17 associated with 70 the fan motor 1 contains the mechanism for driving the bracket 5 around its support by power derived from the armature shaft 18 of the fan motor.

Axially secured to the armature shaft 18 75 in any suitable manner, as by means of co-operating clutch teeth 18 and 19, is a worm 20, which is maintained in engagement with the shaft by means of a plug 21^a screwed into a screw-threaded opening in the wall 80 of the gear box 17. The worm 20 meshes with a worm wheel 21 that is mounted on a short shaft 22 coaxial with the pivot 3 of the fan motor 1, as is clearly shown in Fig. 3. Also secured to the short shaft 22 is a 85 pulley 23, around which extends a belt 24 which also extends around the pulley groove 8 on the lower end of the casting 7. The belt 24 may be composed either of flexible leather belting or of helically wound wire, and, if a leather belt is used, it is maintained under tension by means of a tightening pulley 25 which is carried by an arm 26 pivotally secured to a projection 27 on the bracket 5. The tension exerted by the belt-tightening pulley 25 upon the belt 24 may be maintained by means of a tension spring 28 that is secured, at one end, to the arm 26 and, at the other end, to a sliding plate 29 mounted in suitable supports 29^a on the 100 bracket 5. The tension of the spring may be varied by changing the position of the plate 29 in the supports 29^a. The belt-tightening pulley 25 is disposed at such an inclination and in such a position that the 105 belt is caused to engage the two pulleys 8 and 23, the axes of which are perpendicular to each other, with no tendency to slip laterally from either pulley. It will be evident that the rotation of the armature shaft 110

18 will be transmitted to the pulley 23 through the worm wheel 21 and the shaft 22, and that the belt 24, by reason of its engagement with the rotating pulley 23 and 5 with the stationary pulley 8, will pull the bracket 5 and the fan motors 1 and 2 around the axis of the pulley 8. The speed of this movement of revolution may be varied by changing the relative diameters of the pulley 10 wheels 8 and 23.

The fan motors 1 and 2 are loosely mounted upon their respective pivots 3 and 4, and are maintained at predetermined equal inclinations by reciprocable members 30 and 15 31, the outer ends of which are rounded to engage suitably rounded portions of the fan motor casings. The adjusting members 30 and 31 are pivotally connected, by pivots 32 and 33, respectively, to two bell crank 20 levers 34 and 35, which are provided, at their opposite ends, with slots 40 and 41, both of which are engaged by a pin 42 that is rigidly secured to a nut 43 disposed upon a screw 44. One end of the screw 44 is 25 secured in a bearing 45 in the sleeve 15 and is provided, at its outer end, with a wing nut 46. It will be evident from the drawings, and especially from Fig. 2, that the members 30 and 31 may be moved length- 30 wise by turning the wing nut 46 and thereby moving the nut 43 along the screw 44.

Energy may be supplied to the fan motors 1 and 2 in any convenient manner, such, for example, as by means of a pair of brushes 35 contained in brush holders 50 and 51 and engaging slip rings 52 and 53. The electric circuit may be controlled by means of a switch device 54 operated by means of a chain or cord 55. The conductors supply- 40 ing energy to the brushes and from the slip rings to the fan motors may be arranged in any convenient and usual manner, and are not shown on the drawing.

When the fan motors are positioned with 45 the axes of their armature shafts horizontal, the rotation of the bracket around the hanger 6 is produced solely by the power transmitted through the driving belt. When, however, the fans are tilted either 50 upwardly, or downwardly as shown in the drawing, the torque of the motors will either assist or retard the driving effect of the belt, depending upon the direction of tilt, the direction of rotation of the fan blades, 55 and the consequent direction in which the torque is exerted. The torque effect may, of itself, be sufficient to rotate the bracket, in which case no driving power is transmitted by the belt. In this tilted position 60 of the fans, the driving belt therefore performs the double function of a speed regulator and of a driving element. It maintains a fixed speed ratio between the fan blades and the bracket, and also supplies 65 what ever additional driving force is neces-

sary to rotate the bracket at the required speed.

The structure herein shown and described may be variously modified without departing from the principles of my invention, 70 and it is therefore to be understood that my invention comprehends all such changes and modifications as fall within the scope of the appended claims.

I claim as my invention:

1. The combination with a rotatable support, of a motor mounted on the said support, and belt-operated means driven by the said motor for rotating the said support.

2. The combination with a rotatable support, of a motor mounted upon the said support, a stationary pulley disposed adjacent to the said support, and a belt adapted to be driven by the said motor and passing around the said pulley for rotating the said support.

3. The combination with a rotatable support, of a motor mounted on the said support, a pulley also mounted on the said support and adapted to be driven by the said motor, a relatively stationary pulley disposed adjacent to the said support, and a belt passing over both of the said pulleys.

4. The combination with a rotatable support, of a motor pivotally mounted on the said support, and belt-driven means operated by the said motor for rotating the said support, the angular position of the said motor around its pivot being adjustable without affecting the said rotating means.

5. The combination with a rotatable support, of a motor mounted on the said support, a pulley also mounted on the said support and adapted to be driven by the said motor, a relatively stationary pulley disposed adjacent to the said support upon an axis substantially perpendicular to the axis of the said first-named pulley, a belt passing over both of the said pulleys and a third pulley adapted to engage the said belt and change its direction so that it engages both of the other pulleys in planes perpendicular to their axes.

6. The combination with a support, and a fan pivotally mounted thereon, of means for adjusting the position of the fan with respect to its pivot, the said adjusting means comprising a movable member adapted to engage the said fan and sustain its weight, and a manually operable linkage for moving the said member.

7. The combination with a support, and a fan pivotally mounted thereon and tending to rotate on its pivot under the influence of gravity, of a movable member adapted to engage the said fan and to prevent such rotative movement, and a manually operable linkage for moving the said member.

8. The combination with a support, and a fan mounted upon a horizontal pivot

- thereon and tending to rotate upon the said pivot under the influence of gravity, of a horizontally reciprocable member adapted to engage the said fan and to prevent such 5 rotative movement, and a manually operable linkage for moving the said member.
9. The combination with a support, and a plurality of fans pivotally mounted thereon, of a manually operable linkage for simultaneously 10 adjusting the pivotal position of the said fans.
10. The combination with a support, and a plurality of fans pivotally mounted thereon and tending to rotate around their respective 15 pivots under the influence of gravity, of a plurality of movable members adapted to engage the said fans and to prevent such rotative movement, and a manually operable linkage for simultaneously 20 moving the said members.
11. The combination with a rotatable support, of a motor mounted thereon and adapted to be tilted upon a horizontal axis, and a belt adapted to be driven by the said motor for regulating the speed of the said support and for contributing power to rotate 25 the said support.
12. In a revolving fan mechanism, the combination of a supporting pedestal, a frame member rotatably mounted thereon, a 30 arm pivotally mounted on said frame, a rotary gearing element disposed coaxially with the pivotal axis of the arm, said gearing element having driving connection with the pedestal, a motor carried at the extremity of said arm for movement about said pedestal, a fan operably associated with said motor, and means carried by said arm for actuating said gearing element from said 35 motor.
13. A revolving fan mechanism including a stationary pedestal member, a frame member rotatably mounted on said pedestal member, a pair of arms pivotally supported 40 on said frame member and projecting in opposite directions from the sides thereof, a motor supported upon each of said arms, and gearing mounted within said frame member and one of said arms and interposed between one of said motors and said 45
- 50

pedestal member to rotate the frame member about the axis of the pedestal member, the axis of one of the members of said gearing being coincident with the pivotal axis of the corresponding motor arm. 55

14. In a revolving fan mechanism, the combination of a supporting pedestal, a frame member rotatably mounted thereon, an arm having pivotal mounting on said frame member, gearing housed within portions of said frame member and said arm and comprising a member the axis of which is coincident with the pivotal axis of said arm, a motor supported upon said arm, a fan operably associated with the motor, and means for driving said gearing from said motor to rotate the frame. 60

15. In a revolving fan mechanism, the combination of a supporting pedestal, a frame rotatably mounted thereon, angularly 70 adjustable arms carried by said frame, independently operating motors supported on the respective arms, gearing inclosed within said frame and one of said arms and actuated by one of said motors to rotate the 75 frame and cause the revolution of the motors about the pedestal, and fans operably associated with the motor.

16. A revolving fan mechanism including the combination of a stationary pedestal 80 member, a frame revoluble thereon, a fan and its operating motor carried by the frame and adjustable to vary the inclination of the fan's axis, and gearing comprising a member the axis of which is coincident with the axis of adjustment of the fan and its motor and constituting a positive driving connection between the shaft of the fan motor and the pedestal, whereby the frame and the fan are revolved around the pedestal 85 member at a speed which has a constant definite relation to the speed of the fan-motor shaft. 90

In testimony whereof, I have hereunto subscribed my name this 30th day of Dec. 95 1914.

OLIVER S. JENNINGS.
